Application August 26, 1950, Serial No. 181,677

2 Claims. (Cl. 229—34)

This invention relates to improvements in boxes or cartons and particularly to a knocked-down box or carton wherein the walls are outwardly and upwardly disposed whereby the open upper end of the box or carton has a dimension, at least in one direction, greater than the same dimension along the bottom of the carton in the direction aforesaid.

Boxes or cartons of this general description are old in the art in both cardboard and wood but in the past were of the set-up variety and not knocked-down. By knocked-down construction is meant where the carton or box is partially assembled and shipped in the flat to the ultimate user. In the past the said boxes or cartons of the general type of the present invention had their walls of single material thickness and can probably be best exemplified by the boxes or cartons generally referred to as "berry baskets."

By the present invention the berry basket is provided of foldable material such as cardboard, paste-board, flexible transparent material, and the like, and in a knocked-down condition to be set up by the user and when so set up is provided with walls of considerable thickness and with the said walls hollow and composed of spaced apart inner and outer wall members.

It is therefore the principal object of this invention to provide a carton or box having hollow or spaced apart walls with at least two opposed walls upwardly and outwardly flaring.

Another object of this invention is the provision of a box or carton that will accomplish the foregoing object and wherein the said box or carton is supplied to the user in a knocked-down condition so that the same may have its walls readily erected and locked in erected positions.

A further object of this invention is the provision of a carton or box formed of a single blank of foldable sheet material and wherein each of the walls are of hollow or spaced inner and outer wall members and upwardly and outwardly flare from the carton bottom whereby the open top covers a greater area than the exposed bottom at the lower ends of the walls.

A still further object of this invention is the provision of a box or carton for accomplishing the foregoing object which can be shipped to the user in a knocked-down condition to be readily erected by said user.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a plan view of a blank partly extended and partly folded from which a carton of the present invention may be made.

Fig. 2 is a transverse sectional view through a folded blank as shipped to the user.

2

Fig. 3 is a perspective view of a partially erected carton set up from the blank of Fig. 1.

Fig. 4 is a longitudinal sectional view through a completely erected carton as seen from line 4—4 on Fig. 3.

5 Fig. 5 is a transverse sectional view through a completely erected carton taken at right-angles to Fig. 4 as seen from line 5—5 on Fig. 3.

Fig. 6 is a plan view similar to Fig. 1, of a slightly modified blank whereby a carton having a slight modification over that in Fig. 3 may be produced.

10 Fig. 7 is a transverse sectional view through a knocked-down blank such as disclosed in Fig. 6.

Fig. 8 is a perspective view of a partially erected carton from the blank of Fig. 6.

15 Fig. 9 is a longitudinal sectional view through a completely erected carton from the blank of Fig. 6 as seen from line 9—9 on Fig. 8.

Fig. 10 is a transverse sectional view taken at right-angles to Fig. 9 as seen from line 10—10 on Fig. 8.

20 Fig. 11 is a plan view, similar to Fig. 1, of a blank including the modifications of both Figs. 1 and 6 for providing a carton having the features of each of the cartons in Figs. 3 and 8.

Fig. 12 is a transverse sectional view through a completely folded blank of Fig. 11.

Fig. 13 is a perspective view of a partially erected carton from the blank of Fig. 11.

25 Fig. 14 is a longitudinal sectional view through a completely erected carton of Fig. 13 as seen from line 14—14 on said Fig. 13.

Fig. 15 is a transverse sectional view through the carton of Fig. 13 as seen from line 15—15 on Fig. 13.

30 Fig. 16 is a plan view, similar to Fig. 11, of a blank disclosing a slight modification over the disclosure in said Fig. 11 for providing a carton having the features of each of the cartons of Figs. 3, 8 and 13.

Fig. 17 is a transverse sectional view through a completely folded blank of Fig. 16.

35 Fig. 18 is a perspective view of a partially erected carton from the blank of Fig. 16.

Fig. 19 is a longitudinal sectional view through a completely erected carton of Fig. 18 as seen from line 19—19 on said Fig. 18.

40 Fig. 20 is a transverse sectional view through the carton of Fig. 18 as seen from line 20—20 on said Fig. 18.

Throughout the several views of the drawings similar reference characters are employed to denote the same or similar parts.

45 The drawings illustrate three modifications or exemplifications of the invention which will be described in succession with successive modifications having pointed out the specific details therein over the other modifications.

50 Accordingly, the modification disclosed in Figs. 1 to 5, inclusive, includes a one-piece blank having substantially centrally thereof a main or bottom panel 20 having its sides or edges defined by score or fold lines 21, 22, 23 and 24. For simplification in the following description the score or fold lines 21 and 23 will be described as defining the ends of the blank while the score or fold lines 22 and 24 will be described as defining the sides of the blank. It will be understood that this nomenclature may be reversed since the terms sides are generally reserved for the longer edges of the box or carton while the term ends is ascribed to the transverse or shorter edges. The score or fold lines 22 and 24 each, integrally, hingedly connect with the main or bottom panel a similar extension 25 and 26 which in the erected carton from the side walls while the score or fold lines 21 and 23 each, respectively, integrally, hingedly connect with the main or bottom panel 20 extensions 27 and 28 which in the erected

65 70

carton form the end walls and which extensions will be described in detail.

Accordingly, and since the side wall extensions 25 and 26 are substantially identical, it is believed that a description of one extension, extension 26, will suffice for both. The extension 26 is provided longitudinally thereof with a plurality of parallel score or fold lines 29, 30 and 31 forming, in said extensions, panels 32, 33, 34 and 35. The panel 32 in the erected carton forms the side wall outer wall member and has its ends defined by score or fold lines 36 and 37 which extend, as seen in Fig. 1, downwardly and outwardly from the ends of the score or fold line 24 thereby forming the panel 32, in plan, as an isosceles trapezoid. Hingedly connected to the ends of the panel 32, respectively, by the score or fold lines 36 and 37, are corner pieces 38 and 39 which, as will later be made clear, form bellows corners for the carton.

The panel 33 in the erected carton forms the side wall top wall member or spacer and is of a length equal to the longer side of the panel 32, namely, the score or fold line 29.

In the erected carton the panel 34 forms the side wall inner wall member and has its ends defined by score or fold lines 40 and 41, which like the score or fold lines 36 and 37 are angularly disposed from the outer corners of the side wall top wall member or panel 33. The score or fold lines 40 and 41 instead of being outwardly angularly disposed are inwardly disposed, wherefore, the panel 34, like the panel 32, in plan is an isosceles trapezoid having a position in the blank of the carton reversed to that of the said panel 32. In other words, the longer of the parallel sides of the panel 34 is adjacent the longer of the parallel sides of the panel 32 whereby said panels may be superimposed on one another to have their parallel sides and non-parallel sides coincident. As will later appear, the said panels 32 and 34 are spaced from one another a distance equal to the width of the panel 33. The panel or side wall inner member 34 has integrally, hingedly connected to its opposite ends through the score or fold lines 40 and 41, respectively, tucking flaps 42 and 43 each of which, in turn, has hingedly connected thereto a spacer flap 44 and 45 through, respectively, a score or fold line 46 and 47. The panel or side wall inner wall member 34 is further provided near its outer corners with slots 48 and 49 which are disposed in the panel 34 to be parallel with the score or fold lines 40 and 41 and said slots 48 and 49 cooperate with means for locking the carton walls in their erected positions.

The remaining panel 35 in the erected carton constitutes a glue flap for securing the inner wall member or panel 34 to the main or bottom panel 20 and for this purpose the said glue flap 35 has applied thereto adhesive 50 which, in the modification illustrated in Figs. 1 to 5, inclusive, is applied to the undersurface as seen in Fig. 1.

The end wall forming extensions 27 and 28 are substantially identical wherefore it is deemed sufficient if but one of them be described in detail. Accordingly, extension 27 between the score or fold line 21 and outer extremity thereof is provided with a plurality of parallel score or fold lines 51, 52 and 53 forming in said extension panels 54, 55, 56 and 57. In the erected carton the panel 54 is substantially rectangular in plan and forms the end wall outer wall member and has its ends defined by score or fold lines 58 and 59. The score or fold lines 58 and 59 hingedly connect with the panel 54, respectively, the bellows corner flaps 38 or 39. In order that the said bellows corner flaps or pieces 38 and 39 may be folded they are respectively provided with a diagonal score or fold line 60 and 61.

The panel 55 in the erected carton forms the end wall top wall member or spacer and, as noted above, is intermediate the panels 54 and 56. The panel 56, similar to the panel 54 is substantially rectangular in plan and in

the erected carton forms the end wall inner wall member and is adapted to be disposed transversely of the main or bottom panel between the side walls inner wall members wherefore it is of less length than the panel or end wall outer wall member 54 which spans the space across the side walls outer wall members. The end wall spacer or top wall member 55, therefore, has its ends contoured as at 62 and 63 and which contour may take any suitable or desirable form, that shown in Figs. 1 and 3 simulating a rounded corner.

The end wall inner wall member or panel 56 has its ends defined, in part, by score or fold lines 64 and 65 and, in part, by projecting lugs 66 and 67 which are locking lugs for cooperation with the locking slots 48 and 49 in the side wall inner wall members, as will subsequently be made clear. The end wall inner wall member or panel 56 has hingedly connected to its ends, respectively, by the score or fold lines 64 and 65 spacing tabs 68 and 69 which space the vertical edges of the inner wall member from the outer wall member as will subsequently be made clear. The remaining panel 57 constitutes a spacing flap for spacing the lower end of the end wall inner and outer wall members from one another in erected position.

The blank after being formed as above described has the adhesive 50 applied to the glue flaps of each of the extensions 25 and 26 whereupon the said glue flaps 35 are folded onto the panel 34 on the score or fold line 31, or the said folding of the glue flap is first made whereupon the adhesive 50 is applied thereto. The extensions 25 and 26 are then further folded, respectively, on their score or fold lines 29 to bring the said glue flaps 35 into contact with the main or bottom panel in the position as illustrated in Fig. 1 for the extension 25. Pressure is then applied to insure adhesion of the panel 35 to the bottom.

The blank is now in its knocked-down or folded position with each of the extensions folded as is illustrated for extension 25 in Fig. 1 and as illustrated in cross-section in Fig. 2. The blank or carton in its now folded and knocked-down position is shipped to the user for subsequent erection.

The user upon desiring to erect a carton first raises the folded side walls to be upstanding or normal to the main or bottom panel as shown in Fig. 3. The tucking flaps 42 and 43 each now have their spacing flaps 44 and 45 bent to be parallel with the main or bottom panel 20 whereupon the said tucking flaps are folded to extend transversely of the said carton main or bottom panel as illustrated by the left-hand tucking flap in Fig. 3.

The end wall extensions are now erected which consists in successively raising said extensions after first folding on themselves the bellows corner pieces or flaps 38 and 39 and disposing the said folded corner pieces transversely of the main or bottom panel. Each end wall extension is raised until the outer wall member engages the outwardly and upwardly extending or flaring ends of the side walls, for example, the ends of the panels 32 and 34 as defined by the now aligned inclined score or fold lines 37 and 41. The end wall top wall members or panels 55 are then folded to be parallel with the main or bottom panel 20 and with the contoured ends 62 and 63 thereof resting on the side walls top wall members or panels 33. The inner wall member or panel 56, after having the spacer flap 57 folded to be substantially normal thereto and having the spacing flaps 68 and 69 likewise folded to be substantially normal thereto, is folded to extend parallel with the end walls outer wall members or panels 54 until the locking lugs 66 and 67 snap into the side wall locking slots 48 and 49.

The carton is now in its fully erected position with the end walls extending upwardly and outwardly as seen in Fig. 4 and with the side walls extending upwardly normal to the carton main or bottom panel 20 as seen in Fig. 5. This results in a carton having an open top with

a greater dimension lengthwise than the exposed bottom of the carton lengthwise thereof, while the carton transversely has an open top substantially equal to the exposed bottom of the carton in said transverse direction of the carton.

The modification disclosed in Figs. 6 to 10, inclusive, consists primarily in substituting the isosceles trapezoid side wall inner and outer wall members of the modification in Figs. 1 and 5 for the end wall inner and outer wall members and the similar substitution of the rectangular end wall inner and outer wall members of said modification in Figs. 1 to 5, inclusive, for rectangular side wall inner and outer wall members in Figs. 6 to 10.

The elements in the blank in Fig. 6 as compared with the blank in Fig. 1 are substantially the same and the parts in Fig. 6 are identified by the same reference numerals with a prime (8) added thereto.

In the modification in Figs. 6 to 10, inclusive, the glue flaps 35' for the side walls are shown as provided with adhesive 50' on their upper surfaces and therefore are attached to the main or bottom panel 20 to extend toward the center of said main or bottom panel instead of extending toward the bounding score or fold lines 22 and 24 as illustrated in Fig. 1.

The erected carton in Figs. 9 and 10 shows the carton as having the open upper end thereof longitudinally of the carton as of the same dimension as the exposed bottom or main panel longitudinally of the carton, while transversely the open upper end of the carton is of a greater dimension than the exposed bottom of the carton transversely thereof and including the glue flaps of the side walls as part of the exposed carton bottom. This is the reverse of the carton resulting from the blank of Fig. 1 and as illustrated in Figs. 4 and 5.

The modification illustrated in Figs. 11 to 15, inclusive, has incorporated therein the isosceles trapezoid side wall inner and outer wall members of Fig. 1 and the isosceles trapezoid end wall inner and outer wall members of Fig. 6. Again, the elements of the blank of Fig. 11 are substantially identical with the elements in Figs. 1 and 6, except as modified as just pointed out, and the said elements are identified by the same reference characters with a double prime (") added.

In the blank illustrated in Fig. 11 a slight further modification includes the substitution of tucking flaps 70 and 71 at the ends of the side walls outer wall members 32" instead of the bellows corner pieces 38 and 39 of Fig. 1. This results in a cut line 72 between said tucking flaps 70 and 71 and the end walls inner wall members or panels 54, instead of the score or fold lines 58 and 59 shown in said Fig. 1. The setting up of the blank of Fig. 11 into an erected carton of Fig. 13 is in no wise changed except that the tucking flaps 70 and 71 need not be folded on themselves prior to the erection of the end wall extensions 27" and 28", instead, requiring only that the said tucking flaps 70 and 71 be disposed transversely of the carton main or bottom panel 20, as illustrated at the upper left-hand corner of Fig. 13.

The carton resulting from the blank of Fig. 11 has the end walls upwardly and outwardly flaring, see Fig. 14, as does the end walls of the carton from Fig. 1 as illustrated in Fig. 4. The carton of Fig. 11 also has the side walls upwardly and outwardly flaring, as illustrated in Fig. 15, as does the side walls of the blank of Fig. 6 and illustrated in Fig. 10. In other words, the carton of Fig. 13 has each of its four walls outwardly and upwardly flaring in the same manner as the heretofore known "berry basket."

The blanks of Figs. 6 and 11 are each shipped to the user in their knocked-down position as illustrated by the upper end of said blanks and as further illustrated in Figs. 7 and 12. The user erects the knocked-down blanks of Figs. 7 and 12 in substantially the same manner as he erects the knocked-down blank of Fig. 2 into cartons

for open upper end boxes as illustrated clearly in Figs. 8 and 13.

The modification illustrated in Figs. 16 to 20, inclusive, is substantially identical with the disclosure in Figs. 11 to 15, inclusive, except that the side walls are provided with bottom wall members independently of the closure afforded said side walls by the bottom panel itself. In the drawings, similar to the practice resorted to in connection with the modifications in Figs. 6 and 11, the elements, except for the added elements for accomplishing the result of the present modification, are identified by the same reference characters with a triple prime ("") added.

In the blank of Fig. 16 the glue flap 31" constitutes the side wall bottom wall member 73 having one side thereof defined by the score or fold line 31"" and having its other side defined by score or fold line 74. The score or fold line 74 hingedly connects with the bottom panel the glue flap 35".

15 In forming the blank of Fig. 16 and arranging it in its knocked-down position as illustrated in Fig. 17, the glue flap 35"" is first folded on the score or fold line 74 to lie on the panel 73 to have the adhesive 50"" applied thereto, or the said adhesive 50"" is applied by appropriate mechanism to the under surface of the glue flaps 35"" prior to its folding on the score or fold line 74. The extension 26"" is then folded on its score or fold line 29"" into the position illustrated for the extension 25"" at the upper end of the figure which brings the adhesive 30 into engagement with the side wall outer wall member 32"" outwardly of the score or fold line 24"". The blank is then in the position illustrated in Fig. 17 and is so shipped to the user.

The user in desiring to set up the blank from the knocked-down position of Fig. 17 to the erected position of Fig. 18, and before following the erecting steps above set forth for the blank of Figs. 1, 6 and 11, first raises the side walls to the positions illustrated in phantom lines at 75 and 76 in Fig. 7. In other words the said side walls are first arranged substantially to their ultimate angular positions relative to one another whereupon the said walls are completely erected with respect to the carton bottom and said erected walls locked in their erected positions.

It should be noted that each of the blanks of Figs. 1 and 6 can be similarly modified as was the blank of Fig. 11 and illustrated in Fig. 16 to provide a bottom wall member for the side walls and thereby provide knocked-down cartons which may have their side walls erected or arranged prior to the complete erection of the carton itself.

From the foregoing, it is believed now evident that there has been provided a knocked-down blank erectable into cartons which will have either two opposed sides, two opposed ends, or all sides of a box or carton upwardly and outwardly flaring with respect to the base or bottom thereof.

What is claimed is:

1. A carton of the class described formed from a single blank of foldable material comprising a bottom panel from the edges of which extend wall forming extensions, each extension being subdivided into panels to provide its wall with an inner wall member, a top wall member and an outer wall member with said inner and outer wall members of each wall spaced from one another by its top wall member, each inner and outer wall member panel in each extension being formed as an isosceles trapezoid, two opposed extensions forming side walls with the inner and outer wall member panels thereof each of a substantially equal area, which, upon erection, have their ends in alignment and the ends of their walls upwardly and outwardly extending, the said extensions forming the side walls, each, beyond its inner wall member, having additional panels to provide a bottom wall member and a glue flap beyond the bottom wall member with each of said

glue flaps being adapted for attachment to the inner surface of its side wall outer wall member, the remaining opposed extensions forming end walls each having its outer wall member of an area greater than its inner wall member with said end walls outer wall members each of an area to cover the area between the side walls outer wall members and said end walls inner wall members each of an area to cover the area between the side walls inner wall members, said walls when erected extending at an upward, outward angle each from its edge of the base, and cooperating means on said side and end walls inner wall members for locking the same in erected positions.

2. A carton of the class described formed from a single blank of foldable material comprising a bottom panel from the edges of which extend wall forming extensions, each extension being subdivided into panels to provide its wall with an inner wall member, a top wall member and an outer wall member with said inner and outer wall members of each wall spaced from one another by its top wall member, each inner and outer wall member panel in each extension being formed as an isosceles trapezoid, two opposed extensions forming side walls with the inner and outer wall member panels thereof each of a substantially equal area, which, upon erection, have their ends in alignment and the ends of their walls upwardly and outwardly extending, the said extensions forming the side walls, each, beyond its inner wall member, having additional panels to provide a bottom wall member and a

glue flap beyond the bottom wall member with each of said glue flaps being adapted for attachment to the inner surface of its side wall outer wall member, the remaining opposed extensions forming end walls each having its outer wall member of an area greater than its inner wall member with said end walls outer wall members each of an area to cover the area between the side walls outer wall members and said end walls inner wall member each of an area to cover the area between the side walls inner wall members, said walls when erected extending at an upward, outward angle each from its edge of the base, cooperating means on said side and end walls inner wall members for locking the same in erected positions, and tucking flaps extending from the ends of the side walls inner and outer wall members adapted to be enfolded by the end walls inner and outer wall members.
